CANDLE SUPPORT FOR FLOWER HOLDERS

Margaret E. Shipley, Pittsburgh, Pa.

Application April 21, 1955, Serial No. 502,778

3 Claims. (Cl. 240—2)

This invention relates to a flower holder and particularly to a flower holder adapted to be used on a candle or the like. Many and varied types of flower holders and flower arrangements for use on dining tables and in the home have been heretofore proposed. Such holders have, however, been generally undesirably large, bulky and space consuming. There has not been, to my knowledge, any arrangement by means of which a candle and candle base could be used to hold flowers so as to make an integral arrangement about a candle which would be particularly adapted for use on dining tables and which would permit varied arrangements of flowers with respect to candles without the use of bulky, space-consuming flower holders.

I have invented a new and novel flower holder adapted for use with candles which is simple, economical of space and versatile in its varied combinations and applications.

According to a preferred embodiment of my invention, I provide an expandable ring slidable over a candle and gripping the candle intermediate the length thereof, means on the ring receive the stem of a flower and hold it in a liquid such as water or nutrient solution. Preferably the ring is provided with dovetail grooves receiving a corresponding dovetail member on the flower-receiving means. In the preferred embodiment the flower-receiving means is a hollow cylindrical member which is held in the upright position on the ring.

The many advantages and objects of my invention will become more apparent from a consideration of the following description and the accompanying drawings in which:

Figure 1 is a perspective view of a flower holder according to my invention;

Figure 2 is a perspective view of the flower holder ring of Figure 1;

Figure 3 is a perspective view of a flower-holding means according to Figure 1; and

Figure 4 is a perspective view of an alternative form of my invention.

Referring to the drawings I have illustrated a candle 10 in a candle base or holder 11. A split ring 12, preferably of plastic material, is slidable over the candle 11. Dovetail grooves 13 are provided at spaced inter-

2

vals about the ring 12. Each of the dovetail grooves 13 is provided with stops at the bottom which may be integral with the bottom of the groove. A vial 14 provided with a dovetail projection 15 is attached to the split ring by inserting the dovetail projection 15 in the groove 13. The vial 14 is thus held in an upright position paralleling the candle 11. The vial is filled with water or nutrient solution and flowers 16 are inserted therein.

In the alternative form illustrated in Figure 4, I have shown a candle 20 in a candle base or holder 21. A vial 22 is fixed on a split ring 23 placed in sliding engagement about the candle. A plurality of such vial and split ring assemblies may be placed one above the other along the candle and each ring and vial may be adjustably positioned on the candle to space the vials intermediate the ends thereof.

While I have illustrated and described several preferred embodiments of my invention it will be understood that it may be otherwise embodied within the scope of the following claims.

I claim:

1. In combination, a candle, resilient split ring means extending substantially around the circumference of the candle and in engagement therewith, at least one dovetail groove in said expandable ring means, hollow liquid-containing means, and a dovetail projection on said hollow liquid-containing means fitting into the dovetail groove in the expandable means whereby to removably hold the liquid-containing means on the expandable ring.

2. A flower holder for candles and the like comprising expandable ring means adapted to extend substantially around the circumference of a candle and in engagement therewith, at least one dovetail groove in said expandable ring means, hollow liquid-containing means, and a dovetail projection on said hollow liquid-containing means fitting into the dovetail groove in the expandable means whereby to removably hold the liquid containing means on the expandable ring.

3. A flower holder for candles and the like comprising resilient split ring means adapted to extend substantially around the circumference of a candle and in engagement therewith, at least one dovetail groove in said expandable ring means, hollow liquid-containing means, and a dovetail projection on said hollow liquid-containing means fitting into the dovetail groove in the expandable means whereby to removably hold the liquid-containing means on the expandable ring.
